UNITED STATES PATENT OFFICE

HERBERT M. FRIENDLY, OF CHICAGO, ILLINOIS.

AUTOMATIC TELEPHONE SYSTEM.

Application filed July 14, 1927. Serial No. 205,650.

The present invention relates to telephone systems; more particularly so-called automatic or machine switching telephone systems

5 *General objects.*

The general object of the present invention is to enable the operating concern to establish rates for telephone service for automatic or machine switching telephone systems which 10 will operate to discourage traffic at logical periods of densest traffic and to encourage traffic at logical periods of lightest traffic. Reference is made to my co-pending application for U. S. Letters Patent, Serial No. 191,578, 15 filed May 16th, 1927, with particular reference to the preamble thereof wherein the economic phases of applying service charges in the general manner contemplated by the present invention is discussed, but with particular 20 reference to manual telephone systems. The general advantages accruing to the invention involved in the said co-pending application hold for the present invention.

Reference is also made to my patents 25 1,694,169 granted Dec. 4, 1928, and 1,694,170, granted Dec. 4, 1928. Reference is further made to my copending application Ser. No. 481,259, filed June 29, 1921, with particular reference to switches B and C therein.

30 However, the present invention has specific objects and structure. Among the features of the present invention are:

a. Means requiring the placing of a coin (or token) in a pre-payment collector forming 35 a part of the calling subscriber's station so that unless the coin is first placed in pre-payment device (P) the means for automatically directing the central office automatic switching equipment will continue disabled.

40 Broadly, this feature is not new in the art.

b. Means whereby the timing of the connection will start responsive to the called subscriber responding, and wherein through the agency of a timing switch auxiliary to the first 45 numerical selector of the switch train, the period the connection may be held for a specific toll charge will vary in accordance with the time of day through which the connection endures.

50 c. Means whereby a specific tone will be applied audible to the parties of the connection to apprise them that a substantially definite time remains before the termination of the period allowed for the predetermined toll charge.

d. Means whereby a final tone will be applied audible to the parties of the connection to apprise them that the coin has been deposited in the company till and that the period pre-paid for is about to terminate and that 60 when the period does presently terminate the connection will be destroyed provided another coin is not inserted as pre-payment for the next succeeding period.

e. Means whereby the predetermined time 65 a connection may endure for the fixed predetermined cost will be lengthened for succeeding periods after the first period of a maintained connection while the rate for initial periods remains the same. That is, the second 70 and succeeding periods will be longer for the same time of day for connections which are durating.

f. Means whereby the coin will be refunded 75 upon the calling subscriber hanging up his telephone receiver if the party called does not respond or if the line called is that of a free subscriber so far as incoming calls are concerned. The lines extending to the information, complaint and other departments of 80 the operating concern would come under the latter class of lines.

g. Means whereby the coin will be refunded 85 upon the calling subscriber abandoning the call before initiating the directing or completing the directing of the selection of the line under call.

h. Means whereby during certain hours 90 of the day all calls to predetermined called lines will be charged to said called line. Thus, the grocer for example, will assume the costs 95 of all calls made to him during stated hours of the day, though it will be optional with him by depressing a button at his telephone to transfer the charge to the calling subscriber for any of these calls. The latter calls may 100 be calls appertaining to matters other than orders for his wares. The hours during which the grocer may assume charges for calls may be logical off-peak times and wherein the operating concern may make a special rate for calls of predetermined duration; perhaps of shorter duration than allowed to subscribers generally for the fixed predetermined pre-payment charge in force at that time of day. The latter takes into consideration that in 105 automatic systems the time of holding a connection is the determining factor of cost to the operating concern, almost wholly, since no manual effort is applied by it in effecting 110

and destroying connections; differing in this important respect from so-called manual systems.

i. Means whereby when a called line is encountered busy by a calling subscriber an assessment will be made on a meter device of the called line so as to penalize the subscriber of the called busy line. Moreover, that this last stated operation will only apply through certain (perhaps logical peak hours) hours of the day when it is desired that subscribers maintain an open way for calling subscribers to avoid futile calls for which no revenue is derived from the calling subscriber by the operating concern. It is desired that the called subscriber desist from using the called line or provide a group of sufficient number of lines to carry all traffic offered during said certain hours.

j. A salient feature of the present invention is the feature for refunding the coin to the calling subscriber in the event the primary line switch or the concerned secondary line switch is not able to extend the connection due to all available outgoing trunks therefrom being busy; this responsive to the calling subscriber hanging up his receiver upon hearing the specific tone denoting that the call is futile.

k. Another feature of the primary-secondary line switch arrangement of the present invention is means for barring any secondary line switch group against seizure by a primary line switch if all the trunks normally available from the group of secondary line switches are busy and also bar all the secondary line switch groups against seizure by a primary line switch and indicate by specific tone to the calling subscriber when all the secondary line switches are barred because of being busy.

There are additional operative features of the present invention which will be described in descriptions to follow relating to the exemplary embodiment of the present invention chosen to explain it, having in mind that other features not specifically mentioned will be apparent from the descriptions. The invention is capable of varied modification without departing from its scope as defined by the subjoined claims.

Drawings.

With reference to the accompanying drawings:—

Fig. 1 shows a subscriber's automatic telephone A and coin controlled pre-payment device P leading to a primary line switch L.

Fig. 2 shows two secondary line switches SL and SL' commonly accessible from the primary line switch L, together with sets of chain relays.

Fig. 3 shows a first selector FS³ and its individually companion timing switch TS³ and associated relays accessible from the group of

secondary line switches containing switch SL.

Fig. 4 shows a connector CON and an individually companion timing switch TS⁴ accessible from the group of first selectors containing selectors FS³. It also shows the common clock controlled switch CS⁴.

Fig. 5 shows a called subscriber's line switch LS⁵ and automatic telephone A⁵, together with a respectively designated calling meter and called meter companion thereto.

Sheets containing Fig. 1 to 5 are assembled in numerical order so that the lines extending towards the adjacent margins register.

Fig. 6 shows a preferred modification of Fig. 3.

Figs. 7 and 8 each show a preferred modification of Fig. 4.

Fig. 9 shows a preferred modification of the connector wherein armatures 901 and 902 are added on relay 472.

It has been deemed more simple to disclose the preferred embodiment as a modification of a simpler embodiment than in its more involved, preferred form incorporating Figs. 6, 7 and 8.

Equipment.

The telephone A is of the well known automatic common-battery series type, having an individual pre-payment coin device or "box" P of well known type as used in the Bell telephone system in the Chicago, Illinois, exchange and other places, however, the said device having an additional spring 14 wired in accordance with the present invention. That is, the mechanism for actually depositing or refunding the coin is old, though the wiring arrangement and control of the magnet for operating its armature for depositing or refunding the coin belongs to the present invention.

The line switches L, SL, SL' and SL⁵ are of the well known Lamb general class as described on page 53 of the Third Edition of Hershey's Automatic Telephone Practice, however, modified in details in accordance with the present invention.

The selector FS³ is of the well known Strowger general class (sometimes termed a Powell selector), however, modified in accordance with the present invention. A Powell selector is illustrated on page 60 of the said Hershey book.

The switches TS³ and TS⁴ have the general mechanical details of the line switch L, however, modified in accordance with the present invention.

The connector shown in Fig. 4 is of the well known Strowger general class as illustrated on page 38 of the said Hershey book, however, modified in accordance with the present invention.

The clock controlled device CS⁴ is like shown in Fig. 4 and also described in my pending application Serial No. 191,578, filed

May 16th, 1927, and thus revolves its contact-arm at uniform speed a complete a single revolution each twenty-four hours.

The selector FS³ is shown directly cooperative with the connector CON, the system being a three-digit system, chosen as the simplest to illustrate the present invention. However, it will be understood that the commercial embodiment of the invention would 10 usually involve four or more digits, and under that condition one or more well known Powell selectors or other suitable selectors will be introduced between the selector FS³ and the connector CON; one such selector for each 15 digit over three. Also, a well known so-called trunk repeater may be introduced between the selector FS and the connector CON at any point, without affecting the operation of the present invention in its essentials.

20

Operation.

The operation of the system will be fully understood from exemplary descriptions of the circuit and switch operations in certain 25 assumed calls, having in mind that while a single selector and connector is shown it is only one of a group of similar switches, since the system contemplates a plurality of like calls in simultaneous existence.

30

Initiating a call from telephone A to telephone A⁵.

The calling subscriber will remove the receiver of telephone A from the switch-hook. 35 There will be no operative effect resulting from this until a coin is placed in the coin chute (not shown) of the device P to assume the dotted position 9 which will cause the normally free springs 12, 13 and 14 to engage together as indicated by the dotted positions thereof. This closes a series path from ground, armature 15, springs 14 and 13, receiver and transmitter of telephone A, armature 16 to the winding of slow-releasing line 40 relay 17, the latter said relay actuating. The windings of the polarized electro-magnet 18 of the device P will be in a path from ground to the lower line talking conductor closed by the springs 12, 13 and 14.

50 The line switch L will operate in the well known manner to seize the trunk its wipers are shown resting upon or will rotate in a hunting operation and seize the first idle trunk line tested through the operation of seizing (also termed "bridge-cut-off") relay 20.

60 The line switch L has access to two groups of trunks corresponding to two groups of secondary line switches of which SL and SL' are each one switch of the two groups, respectively. It will be first assumed that the trunk leading to the secondary line switch SL is seized so that the winding of slow-releasing line relay 201 is now in a series path 65 including telephone A and armature 202,

whereupon the switch SL will operate in the well known manner and seize the trunk its wipers are shown resting upon or will rotate in a hunting operation and seize the first idle trunk line tested through the operation 70 of seizing relay 204.

It will be first assumed that the trunk leading to first selector FS³ is seized, so that the windings of line relay 301 is now in a series path including the telephone A and the upper winding of electro-polarized relay 302. The switches L and SL are maintained operated in the well known manner due to the slow-releasing characteristic of relays 17 and 201 until slow-releasing release relay 304 actuates and applies ground from its armature 305 over release trunk 306 to the winding of slow-releasing relay 307, the latter said relay actuating to apply ground from armature 308 to back release trunk conductor 309. The 80 attraction of armature 308 occurs before relay 201 has had time to retract its armatures, so that there is no lapse of ground to the upper winding terminals of relays 20 and 204. The maintaining of the switches L and SL is 90 thus dependent upon maintaining ground on conductor 309 by armature 308, or alternatively, as will appear presently, by the off-normal position of wiper 315 of the wiper group 312 to 316 on shaft 317 of the timing 95 switch TS³.

Calling subscriber abandons call.

If the calling subscriber now abandons the call by replacing his receiver on the switch-hook, the relays 301, 304 and 307 will deactivate in sequence. Before relay 307 deactivates ground is applied from retracted armature 305, armatures 319, 320, bank terminal 321, wiper 316, interrupter armature 100 on motor magnet (designated MM³) of the timing switch TS³, causing the wipers to be stepped to the second bank position. When the armature 308 retracts its ground is applied through armature 322 to bar 323 engaged by wiper 316 so that the motor magnet 105 will drive the wipers on shaft 317 by interrupter action to restore them to the drawn position.

It will be noted that wiper 315 maintains 115 ground on bar 324 and to conductor 309 after the retraction of armature 308 to hold the switches L and SL in seizure. However, when wiper 312 encounters bank terminal 325 it causes relay 326 to operatively energize to attract all its armatures, but for the sole object at this time of completing a path from ground through negative battery RB, armature 327, upper winding of relay 328 armature 329, lower talking conductor 120 through the winding of polarized magnet 18 to ground. The latter said magnet, due to its polarized property operates to refund the coin to the subscriber, in the well known manner. The springs 12, 13 and 14 are now 125 130

free and the circuit including telephone A is open at the switch-hook and also at springs 13 and 14. When the wiper 315 moves off the bar 324 ground is thereby removed from 5 conductor 309, whereupon the switches L and SL restore subject to normal use by reason of relays 20 and 204 deactuating, respectively.

In this connection it will be noted that 10 when the relay 326 actuates the armature 332 (which is adjusted to make first) will close ground derived through common retardation coil 334 to re-energize the upper winding of relay 301. However, due to the rapid movement of the wiper 312 this closure is maintained a very brief time; insufficient for the 15 relays 304 and 307 (which are somewhat slow in attracting their armatures due to the stated slow-releasing characteristic affecting the 20 actuation) to both actuate to cause ground to be on bank terminal 321 when the wiper 316 returns. Otherwise (with ground on bank terminal 321), the wipers on switch TS³ would be caused to thereupon make a 25 false cycle of operation, however, to no operative confusion, since the call is completely abandoned when the wiper 315 moves off bar 324. The object of armature 332 and coil 334 will appear presently.

30 *Calling subscriber elects to complete call in place of abandoning it—Sends first digit.*

If the calling subscriber in place of the assumed abandoning of the call elects to complete it he will operate his calling device in accordance with the first digit 1, which will cause relay 301 to momentarily retract its armature 335, applying ground through armatures 336 and 337, winding of slow-releasing series relay 338 to the winding of the vertical magnet (designated Vert. M.). This will raise the shaft 340 carrying wipers 341 to 343 into alignment with the first level of bank terminals of which terminals 345 40 to 347 constitute the first set cooperative with wipers 341 to 343, respectively. If it is assumed that the connector CON (corresponding to bank terminals 345 to 347) is idle, and having in mind the well known selective and 45 test circuits present in the selector FS³ of the present invention, the connector CON will be seized by the actuation of switching relay 350, whereupon the relay 301 will become disconnected.

50 The windings of the line relay 401 of the connector are now in series with the telephone A, there being no intermediate affecting attachments. Slow-releasing release relay 402 is now operatively energized by armature 403, which causes armature 405 to apply its ground to the release trunk 406, bank terminal 345, wiper 341, armature 351 to the lower winding of relay 350, for maintaining the selector FS³ in seizure and the relay 307 55 energized, before armature 305 retracts, so

that no lapse of ground on the release trunk 306 occurs.

Calling subscriber sends last two digits to set the connector.

70

The operation of the connector, effective responsive to the calling subscriber sending the last two digits 11 of the called telephone number being well known, in view of the stated reference to Hershey's book, the detailed 75 operation of the connector in effecting connection to the called line leading to telephone A⁵ will be understood. It will therefore be assumed that the wipers 407 to 410 are now resting on bank terminals 411 to 414, respectively. Other features and modifications of the connector specific to the present invention will appear presently.

The armature 415 now applies its ground to operate the line-cut-off relay 501 of the 85 line switch LS⁵ and to place a guarding busy-ground on the private normal conductor 502 and its multiplied bank terminals. Ringing current from source designated "R. Gen." in Fig. 4 is now being applied effective to the 90 signal bell of the called telephone A⁵, in the well known manner.

Clock operated device CS⁴.

Before detailing the operation of the connector (in view of the present invention) responsive to the called subscriber removing his receiver from the switch-hook in responding to the call, reference is made to the clock operated device CS⁴. This device has a 95 grounded contact-arm 416 which revolves making a single cycle in a twenty-four hour period, as has been referred to before. It shows twenty-four equally angular segments; one for each hour, though it will be understood that the segments may be of any convenient angular size, corresponding to any desired period of the day, to exercise the desired control. The switch-arm 416 is shown resting on the segment corresponding to 100 12 o'clock noon to 1 o'clock p. m. The segments from 1 o'clock a. m. to 6 o'clock a. m. are multiplied together and connected to the switch-arm 417. The segment corresponding to 6 o'clock a. m. to 7 o'clock a. m. is connected to the switch-arm 418, and the segment corresponding to 9 o'clock a. m. to 10 o'clock a. m. is connected to switch-arm 419. The unconnected segments also run to switch-arms (not shown) similar to 417 to 419, but the latter referred to switch-arms are not shown in order to avoid unduly involving the disclosure.

When the switch-arms 417 to 419 are in the 115 positions drawn it provides for grounding conductor 420 when the contact-arm 416 is resting upon the corresponding segment group 421 and segments 422 and 423. Likewise, when the switch-arms 417 to 419 are in the dotted positions it provides for ground- 120 130

ing conductor 425 when the contact-arm 416 is resting upon the corresponding segment group 421 and segments 422 and 423. That is to say, during the twenty-four day conductor 5 420 or alternatively conductor 425 will be grounded by the contact-arm 416 in accordance with a pre-arranged schedule which may be varied at will, as for example, for the different days of the week and for various 10 holidays in accordance with published schedules. In view of the reference to Fig. 5 of my co-pending application Serial No. 191,578, filed May 16th, 1927, it is thought more detailed discussion of the contemplated modifications 15 of the device CS⁴ covering multiple and fractional hour segments will not be necessary in imparting a comprehensive disclosure of the device CS⁴.

It will be noted that when conductor 420 20 is grounded all armatures corresponding to 427 in the connector group will be grounded, which provides for operatively energizing the reversing relay 428 and locking it to the release trunk 406, when the called subscriber 25 responds, for an object which will appear presently.

And, it will be noted that when the conductor 425 is grounded all armatures corresponding to 430 in the connector group will be 30 grounded, which provides for applying this ground through armature 431 to bank terminal 432 on switch TS⁴, for an object which will appear presently.

35 *Subscriber on called line responds.*

It will be assumed that the call is made shortly after 3 o'clock a. m. and that the switch arm 417 is in the position as drawn, and therefore the conductor 420 is grounded. 40 When the subscriber on the called line removes his receiver from the switch-hook the ring-cut-off relay 435 will operatively energize to disconnect the ringing current and cut-through the talking conductors. Ground 45 from contact-arm 416 will be applied through armature 427 to the lower winding of relay 428 causing the latter said relay to actuate and lock by its upper winding and armature 436 to the release trunk 406, reversing the 50 direction of current applied through the calling telephone A. This will cause the current in the upper winding of relay 302 to energize cumulatively with the lower winding thereof, thereby attracting the armatures thereof. 55 The current in the polarizing (lower) winding of relay 302 is augmented by the short-circuiting of resistor 353 by the upper armature of said relay 302, which makes first, the polarizing winding then being able to sustain the armatures regardless of the direction 60 of current in the upper winding.

In this connection, it will be noted that the ground interrupter VI³ revolves at a speed which varies with the time of day and 65 may be considered similar to and operated and

controlled like interrupter 16 of my said co-pending application. The ground interrupter CI³ revolves at constant speed and is similar to and corresponds to interrupter 78 of my said co-pending application. 70

The relay 302 actuating and locking responsive to the subscriber on the called line removing his receiver, ground impulses from interrupter VI³ are applied through armatures 354, 355, bar 356, wiper 314 lower winding of relay 328, armature 327 to positive deposit battery DB to ground, the relay 328 operating responsive to the ground impulses from the interrupter VI³. The armature 357 will apply ground to the motor magnet MM³ 80 and thereby cause the wipers 312 to 316 to start stepping consistent with the speed of the ground interrupter VI³. When wiper 314 engages bar 358 the motor magnet comes under the control of the ground interrupter CI³ over an obvious circuit path. Thus, regardless of the variable speed of the interrupter VI³ the space embraced by the bar 358 will always be passed over at a constant rate occupying a substantially uniform time for 90 all times of the day.

Advance tone a definite time before end of period.

At the time wiper 314 engages bar 358 wiper 313 engages bank terminal 359 so that tone from source PT³ will be applied through wiper 313, armature 360 to the lower talking conductor, audible to the parties to the connection. This tone apprises that a substantially definite time remains within the ensuing period before the coin will be deposited in the company till and the connection thereafter broken down, and to terminate the conversation or be prepared to insert another 105 coin for a succeeding period.

Deposit of the coin in the company till.

When the wiper 312 engages bank terminal 325 and armature 357 thereafter attracts, the 110 relay 326 will actuate as before described; this time applying positive deposit battery DB from ground, armature 327, upper winding of relay 328, armature 329 lower talking conductor, winding of polarized magnet 115 18 to ground, the armature of the latter said magnet moving in the direction to deposit the coin in the company till. This opens the circuit path through the telephone A at springs 13—14. Under ordinary conditions, 120 this would deenergize the line relay 401 in the connector and cause the connection to be destroyed. However, it will appear presently that under the present condition the connection will not be forthwith destroyed.

At the same time that the coin is deposited in the company till the tone source FT³ is applied through bank terminal 361, wiper 313, armature 360, to the lower talking conductor, audible to the parties of the connec- 130

- tion, apprising them that the period has about terminated and that a short time remains in which to deposit a coin for a continuation of the connection or it will be destroyed by self-applied automatic means involved in the switch TS^3 . However, when the wiper 313 moves to bank terminal 362 the retardation coil 363 is bridged across the talking path to maintain the relay 401 energized in order to maintain ground on the release trunk 406 so that the connection will not be destroyed at this time. If there is no coin in the pre-payment coin chute of device P at the time wiper 313 moves from bank terminal 362, and the bridge including coil 363 is thereby opened, there will be no path for energizing the relay 401 so it will deactivate and the switches will restore in an obvious manner, in view of the references to well known switches.
- 20 It will be noted here that at the time relay 326 actuated to effect the deposit of the coin in the company till the armature 329 opens the energizing circuit for relay 401, and the spring 14 of the prepayment device P also 25 does this, so that ground applied through the common retardation coil 334 and armature 332 to the upper talking conductor serves to maintain the relay 401 energized by way of a new path.
- 30 *Second coin deposited maintains connection.*

If the calling subscriber inserts a second coin in order to re-operate the springs 12, 13 and 14 before the wiper 313 moves off bank terminal 362 there will be an energizing circuit path through the telephone Λ when the bridge including the coil 363 is opened, having in mind that the parties may converse past the said bridge until the connection is destroyed, the condenser 330 maintaining the talking path operative while the armature 329 is attracted for a brief time but sufficient to operate the magnet 18 of the prepayment device P.

45 *Timing of call starts when called subscriber responds.—Called subscriber may assume call charge on his "called" meter in lieu of calling subscriber's meter.*

50 The switch TS^3 starts responsive to the relay 302 actuating when the called subscriber responds. It will be noted that this is due to the switch-arm 417 being in its drawn position, indicative that all calls at that hour 55 are positively paid for by the calling party. However, had the switch-arm 417 been in the dotted position wherein the conductor 425 is grounded in place of conductor 420, the charge would be assessed to the called subscriber, 60 unless the called subscriber by a specific manual operation, as by momentarily depressing key 505, transfers this charge to the calling line as will appear presently.

It will be noted that the battery energizing 65 the transmitter on the called subscriber's tele-

phone A^5 is derived through the retardation coil 440 as a back-bridge, it being applied through the windings of differentially wound relay 441. That is, the usual reversing armatures on the back-bridge relay are not present; the reversing being done by a specifically connected relay 428 of the present invention.

70 It will be further noted that due to conductor 425 being grounded when the relay 435 actuates armature 427 has no operative function, while armature 430 applies ground through armature 431 to bank terminal 432. The wipers 445 to 448 on shaft 449 being in the drawn position the said ground application will be applied through interrupter armature to the motor magnet MM^4 , causing the wipers 445 to 448 to move off to first off-normal bank position wherein wiper 448 is resting on bar 450 and the motor magnet MM^4 is thus under the control of ground interrupter VI^4 corresponding to interrupter VI^3 in general characteristics and variations of speed with the time of day; in fact may be the same interrupter as VI^3 . In the same manner the ground interrupter CI^4 corresponds in general to interrupter CI^3 ; in fact, 85 may be the same interrupter as CI^3 .

85 However, it will be understood that the operating concern may desire to grant special rates to subscribers who desire to pay for calls 90 made to them at certain predetermined hours and moreover, to have these rates comprehend a shorter holding time than applied to general calls paid for by the calling party. Subscribers receiving orders from housewives in the 95 early morning hours before the business or 100 logical peak occurs and who have, as a rule, no occasion to hold the connection long would come under this class. Under this arrangement the ground interrupter VI^4 would be 105 operated at a speed to effect faster ground impulses during such times when the called subscriber pays for the call and the pre-payment is accordingly refunded, as will appear.

110 *Meter of called subscriber paying for incoming call registers a plurality of times for the period.*

115 It will be noted that if the called subscriber responds under the condition of the switch-arm 417 being in the dotted position the relay 428 will not be caused to actuate to in turn cause the relay 302 to actuate to start the movement of the switch TS^3 . As the wiper 445 engages bank terminals 452 to 456 successively five applications of ground will be made through wiper 445, armature 457, wiper 407, bank terminal 411 to the called meter 507, registering five points for the predetermined period. The parties to the connection will be apprised of the definite time before the termination of the period when tone source PT^4 is applied through bank terminal 458, wiper 446, armature 459 to the lower talking conductor, and again apprised just be- 120 125 130

fore the period terminates when the tone source FT^4 is applied through bank terminal 460, wiper 446, armature 459 to the lower talking conductor. The parties may hold 5 the connection indefinitely while the conductor 425 is grounded and the charges will continue to be assessed on the called meter 507 of the telephone T^5 . However, if the conductor 420 becomes grounded in place of conductor 10 tor 425 while the connection endures, due to the position assumed by contact-arm 416 this ground will be applied through armature 427 to the lower winding of relay 428, causing the latter relay and relay 302 to actuate. This 15 opens the path to the called meter 507 of telephone T^5 and starts the operation of the switch TS^3 , whereupon the charge is accruing to the calling subscriber. The coin will be deposited in the company till, as before described, 20 when the wiper 312 engages bank terminal 325 and another coin will need to be inserted before wiper 313 leaves bank terminal 362 in order to prevent the connection being destroyed by the self-automatic operation of 25 the switch TS^3 referred to before.

Called subscriber may transfer accruing charge from his line to line of calling subscriber.

30 Let it be assumed that after the called party responded and conversed with the calling subscriber, while the wiper 445 is progressing over bank terminals 452 to 456, and has assessed one or more points on the called 35 meter 507, the called subscriber desires to transfer the charges thereafter accruing to the calling subscriber, the benefits derived from the call perhaps being primarily his. The called subscriber will depress button 505 40 which will upset the differential energization of the relay 441 and cause the armature 462 to apply its ground to the upper winding of relay 428, causing the latter said relay to lock. This in turn causes the relay 302 to 45 actuate and lock, which causes the switch TS^3 to start its cycle of operations which have been described. The actuation of relay 428 disables the application of ground impulses to the called meter 507.

50 *Coin refunded when calling subscriber hangs up receiver if call charge is assessed to called subscriber.*

Let it be assumed that the called party is 55 being assessed the accruing charges and that he does not elect to transfer the charges to the calling subscriber, and the conversation is terminated and the parties hang up their respective receivers. The destroying of the 60 connection is in the hands of the calling subscriber. Having in mind that the wipers of the switch TS^3 have remained at normal, it will be noted that relays 401, 402, 350 and 307 restore in sequence, so that when armature 65 319 retracts it applies ground from arma-

ture 305 through armature 319 and 320 to bank terminal 321 to cause the wipers on shaft 317 to move off-normal and thereafter advance by interrupter action. When wiper 312 engages bank terminal 325 and relay 326 70 thereupon actuates, refunding battery source RB will be applied over the lower talking conductor to operate the magnet 18 to refund the coin to the calling subscriber, in the manner before described when the initiated call 75 was abandoned. It will be noted that since wiper 315 engages bar 324 before armature 308 retracts the switches of the train will be maintained in seizure until after wiper 315 moves off bar 324 to the position shown in the 80 drawing, the coin having been refunded in the mean time as described as above referred to.

Connector is disabled for releasing if companion timing switch is off-normal. 85

In this connection, it will be noted that while the maintaining of ground on the release trunk back to the line switch L depends first upon the ground applied from armature 405, the connector is disabled from releasing until the wipers of the switch TS^4 are restored to the drawn position so that the toll will be assessed on the called meter 507, before the wipers of the connector are retracted 95 from the bank terminals of the called line. That is, the release magnet of the connector (designated Rel. M.) is energized over the usual path, but with the wiper 446 and bank terminal 465 introduced in the path. 100

It will be noted that when the armature 405 retracts it applies ground to restoring bar 467 to cause the motor magnet MM^4 to restore the wipers by self-interrupter action of the said magnet MM^4 , while the armature 468 105 disconnects the wiper 448 from the winding of the said motor magnet so as to not affect the impulses from the interrupters VI^4 and CI^4 .

The selector FS^3 will restore its wipers 110 forthwith after armature 405 retracts, but ground will be maintained on the release trunk 309 until after the wipers of the switch TS^3 move to the position as drawn. In view of the references, it is thought the restoration 115 operations of the various switches will be understood, though the switches incorporate circuits and functions specific to the present invention.

Timing of preliminary and final tone sources for brief application. 120

The interrupters PI^3 and FI^3 are so timed with respect to the interrupter CI^3 that they will very briefly apply tone while the wiper 125 313 is resting on bank terminals 359 and 361, respectively, the interrupter PI^3 being constructed to apply the tone from source PT^3 even more briefly than interrupter FI^3 admits of the tone from source FT^3 to be ap- 130

plied. The interrupters VI³ and CI³ are constructed so that the ground applications therefrom are brief with respect to the time between the ground applications.

5 The interrupters PI⁴ and FI⁴ are so timed with respect to the interrupter CI⁴ that they will very briefly apply tone while the wiper 446 is resting on bank terminals 458 and 460, respectively, the interrupter PI⁴ being constructed to apply the tone from source PT⁴ even more briefly than interrupter FI⁴ admits of the tone from source FT⁴ to be applied. The interrupters VI⁴ and CI⁴ are constructed so that the ground applications therefrom are brief with respect to the time between the ground applications.

It will be noted, in this connection, that the wiper 312 is grounded but briefly at each stepping time so that the relay 326 is only 20 briefly energized while the wiper 312 rests on bank terminal 325. The same holds for the wiper 445 so that the called meter 507 of the called subscriber's line will be only 25 momentarily energized as the wiper engages the bank terminals 452 to 456 for a larger time, respectively.

Number of assessments against the calling subscriber's line registered on meter specific to his line.

30 In addition to or in lieu of the pre-payment coin device P a call meter 25 is installed companion to the line switch L. It will be noted that only if the relay 302 actuates responsive to the relay 428 actuating will ground on armature 370 be applied through armature 371, conductor 372 and over the obvious circuit path to the winding of the meter 25, operating it one time. That 35 is, the meter 25 will record the number of coins in the pre-payment device P, or the number of periods used if the pre-payment device P is not employed. The device P may therefore be dispensed with and the subscriber's line connected directly from telephone A to armatures 15 and 16 and therefore not dependent upon the closure of springs 13 and 14. The meter 25 may be common to a group 40 of calling lines.

50 Assessing charge to called subscriber responsive to encountering his line busy.

Let it be assumed that when the private wiper 408 of the connector is set upon the 55 bank terminals of the called subscriber's line it is busy guarded by ground being on the private bank terminal 412. The busy relay 471 will lock, having in mind it may be actuated before the wiper 408 is set upon the bank terminal 412, due to passing over a grounded bank terminal. Slow-releasing rotary relay 472 will be actuated during the operation of the rotary magnet (designated Rot. M.), and for a time thereafter consistent with its slow-releasing period, after the impulses to the

rotary magnet cease. With the relay 471 actuated, applying busy tone to the calling line and the relay 472 deactuated, ground through switch-arm 473 is applied through armatures 474 and 475, wiper 407, bank terminal 411 to the called meter 507, thereby assessing one point thereon. The meter 507 may be common to a group of called lines.

Whether the charge for call will be assessed to busy called line is dependent upon time of day call is made.

The switch-arm 473 may be variously set by the central office attendant in accordance with rate schedules. For example, if the 80 switch-arm 473 is set upon the terminal 475, the assessment against the called line for an encountered busy condition thereof will depend upon the conductor 425 being grounded in accordance with the time of day. And if the switch-arm 473 is set upon terminal 476 the latter said assessment against the called line will depend upon conductor 420 being grounded in accordance with the time of day. And if the switch-arm 473 is set upon the 90 terminal 477 no latter said assessment will be made against the called line.

Means for refunding coin if subscriber's line cannot be extended to first selector due to busy trunk condition—A secondary line switch cannot be seized if no outgoing trunks accessible therefrom are idle.

It will be noted that a set of chain relays 205 to 209 are companion to the group of 100 trunks accessible from the group of secondary line switches of which switch SL is one. Also, that these are respectively energized when the corresponding private terminals are grounded, so that conductor 210 will be 105 grounded only when all the trunks accessible from switch SL are busy. That is, relay 212 will be actuated when its corresponding group of trunks are busy.

Also, it will be noted that a set of chain relays 215 to 219 are companion to the group of 110 trunks accessible from the group of secondary line switches of which switch SL' is one. Also, that these are respectively energized when the corresponding private terminals are 115 grounded, so that conductor 220 will be grounded only when all trunks accessible from switch SL' are busy. That is, relay 222 will be actuated when its corresponding group of trunks are busy.

There may be any number of groups of trunks, two only being shown leading from the secondary line switches SL and SL'. However, four relays 212, 222, 223 and 224 are shown, wherein each of the latter relays 125 correspond to a group of secondary line switches.

It will be noted that when relay 212 is actuated each release trunk conductor as 230 is 130 busy-grounded to bar it from seizure by a

line switch as L, there being an armature on relay 212 for each secondary line switch as SL of its corresponding group of secondary line switches.

5. It will be noted that when relay 222 is actuated each release trunk conductor as 231 is busy-grounded to bar it from seizure by a line switch as L, there being a direct connection from conductor 220 to the resting contacts of all armatures corresponding to 235. This ground is removed from the release trunk conductor 231 by the attraction of either armature 235 or 236. Thus, normally all idle release trunk conductors 231 will be tied to conductor 220 and each untied as the corresponding switches are seized. However, a switch of the group containing switch SL' cannot be seized if the conductor 220 is grounded by the closure of the chain ground 20 by relays 215 to 219.

- The release trunk conductors as 230 are not normally tied together since the conductors as 238 are individual to each armature as 240 and an armature as 241 on relay 212. 25 That is to say, if all trunks of a group accessible from line switch SL or SL' are busy, the switches SL or SL', as the case may be, cannot be seized. This is in order to prevent a secondary line switch being seized in 30 a group wherein there is no idle outgoing trunk as denoted by the conductor 210 or 220 being grounded. The conductor 220 may be falsely busy-grounded at the instant of seizure of an idle secondary line switch as SL', 35 but only for a very brief, almost inappreciable time so far as any affecting operative function is concerned. This would only endure after the idle trunk is seized until the armature corresponding to 235 thereof at- 40 tracts to free it from conductor 220.

- It will be noted that bank terminals 245 and 246 accessible from switch SL lead to the tone source ST² to minus (refunding) battery RB' and through retardation coil 250 to the latter said battery. This also applies for 45 bank terminals 247 and 248, respectively. The private bank terminal 251 is normally connected through armatures 252 and 253 to ground to guard the bank terminals 245 and 246 against seizure. The private bank terminal 255 is normally connected through 50 armatures 256 and 253 to ground to guard the bank terminals 247 and 248 against seizure, it being noted that armature 253 is common to 55 the grounding of both private bank terminals 251 and 255.

- It will be noted that when all trunks accessible from switch SL are busy the terminals 245 and 246 are unguarded, and that when 60 all trunks accessible from switch SL' are busy the terminals 247 and 248 are unguarded. This is so in the event there is a sole idle trunk accessible from either switch SL or SL' and two line switches as L seize a switch as SL 65 or SL' wherein but one of the switches will

be enabled to seize the sole idle trunk the other switch involving the futile extension will then be caused to seize the bank terminals corresponding to tone source ST². The calling subscriber of the futile call will thus be apprised by the distinctive tone from the latter said source. Also, the refunding battery RB' applied through the retardation coil 250 will operate the magnet 18 in the device P to refund the coin to the calling subscriber.

In this connection, it will be noted, that the subscriber's line will become opened at spring 14. No ground being applied back over the private terminal 251, or 255 as the case may be, the switch as SL, or switch SL' as the case may be, would not in any event remain in seizure beyond the sustaining period of the relay 201, or 260, as the case may be.

Calling subscriber notified by specific tone if initiated call is futile because of all trunks outgoing from his primary line switch or the secondary line switches are busy, respectively.

In the event, when all trunks normally accessible from the secondary line switches SL and SL' are busy, the relays 212 and 222 to 224 will be actuated and ground chained to actuate relay 265. This will remove the ground applied from the resting contact of armature 253, so that not only will the ground be removed from the bank terminals 245 and 255, but ground will also be removed from bank terminals as 31 of the primary line switch L to unguard bank terminals as 32 and 33, so that any subscriber now initiating a call wherein no extension can be made due to all outgoing trunk paths being busy, the terminals corresponding to 32 and 33 will be seized and distinctive tone from source PT² applied audible to the calling subscriber. The minus (refunding) battery RB'' applied through retardation coil 275 will cause the refunding of the coin in the same manner as when a refund is made by battery RB' applied through coil 250.

It will be understood in this connection that all terminals corresponding to 251, 245 and 246 of the group containing switch SL will be in multiple, respectively. The same holds for all terminals corresponding to 255, 247 and 248 of the group containing switch SL'. And the same holds for the primary line switches as L wherein all the terminals corresponding to 31, 32 and 33 are tied together, respectively.

It will thus be clear that not only are the primary line switches as L barred from seizing a secondary line switch wherein there is at the time no idle outgoing trunk available from the secondary line switch, but in the event of an all busy trunk condition outgoing from the secondary line switch seized occurring after the seizure of a secondary line switch the calling subscriber concerned will

be notified of the futility of the call by a specific tone and will have his pre-deposited coin refunded forthwith.

Also, in the event there are no idle trunks outgoing from the primary line switch as L 5 the calling subscriber concerned will be apprised of the fact that the call is futile by a specific tone and have his pre-deposited coin refunded.

It will be noted that the present invention 10 comprehends armatures 240, 271 and make contact 272 of switch SL, and armatures 235, 236 and make contact 275 of switch SL', together with interlinked circuits, having in mind that the line switch L is not new in the 15 art and in itself without consideration of its cooperative circuits is not a part of the present invention. What is shown in switches SL and SL' beyond what is shown in the switch L belongs to the present invention. 20

Preferred modifications.

Fig. 6 shows a preferred modification of Fig. 3 wherein an added armature 601 on 25 relay 326 causes added relay 602 to actuate and lock by armature 605 to the release trunk 309 so that the ground interrupter VI³ is disconnected and the ground interrupter VI⁶ is connected in its place by armature 604. 30 The latter interrupter while variable with the time of day, as is interrupter VI³, runs slower so that the time required for the wipers 312 to 316 to pass over the space embraced by bar 356 will be longer under the 35 influence of the interrupter VI⁶ than under the influence of the interrupter VI³. That is, for the same time of day the periods after the first for a maintained connection will be longer for the same assessment. The interrupters VI³ and VI⁶ may have speeds which 40 are correspondingly variable during the day. Thus, the percentage increase in the allowable time for succeeding periods over the initial period may be uniform, but of course, 45 this is not necessarily so.

Fig. 7 shows a preferred modification of Fig. 4 wherein when wiper 445 applies ground to bank terminal 470 relay 701 is caused to lock by armature 702 to the release 50 trunk 406. Armature 703 disconnects interrupter VI⁴ and substitutes interrupter VI⁶ therefor. The latter interrupters may bear the same relation to each other as interrupters VI³ and VI⁶ in Figs. 3 and 6, for a 55 similar object, but with respect to assessments on the called meter as 507 of the line called.

Fig. 8 shows the retardation coil 440 in Fig. 4 changed to a relay 801 having an armature 60 and the relay 441 changed to relay 803 having cumulative windings in place of differential, and the armature 804 of relay 803 provided with a grounded resting contact in place of a make contact. The relay 803 is marginally adjusted. In the event the called

subscriber at telephone A⁵ wishes to cause the relay 428 to lock he will momentarily depress button 508 to remove the short-circuit from the resistor 509 to attenuate the strength of current traversing the cumulative windings of marginally adjusted relay 803 so that it will retract its armature 804, while armature 802 remains attracted, thus causing a ground impulse to be applied to energize the upper winding of the relay 428 75 to cause the reversal effective to actuating relay 302. That is, in place of applying ground by means of button 505 the inclusion of resistance involved in the resistor 509 is employed. One or the other button 505 or 508 80 will not be employed.

Fig. 9 shows a preferred modification of the connector wherein armatures 901 and 902 are added on relay 472. Armature 901 energizes added slow-releasing relay 903, so 85 that relay 903 will sustain a short time after relay 472 deactuates. During the time relay 903 is actuated while relay 472 is deactuated, tone from source T⁹ is applied to the called line, whether it is idle or busy, so that if it 90 is busy the party thereon will be apprised that a calling party is seeking connection with his line and will perhaps hasten the termination of the ensuing call so his line may be available if a subsequent attempt to connect with 95 it is made.

The conductor from the switch-arm 473 is run to the armature 905 so that the path from switch-arm 473 to the make contact of armature 474 is only closed while relay 903 100 is actuated. This obviates energizing the called meter 507 for the entire time the connector is left into selective relation to the busy called line.

In this connection, it is to be understood 105 that the said preferred embodiments, excepting that disclosed by Fig. 8, are to be assumed as part of the exemplary embodiment, shown as modifications in order to make the descriptions as simple as possible. That is, the preferred embodiments, so termed, are not intended as merely possible alternative embodiments, though obviously they may be omitted without departing from the spirit of the invention defined by certain subjoined 110 claims which may not require all disclosed structure to support them.

I claim:—

1. In an automatic telephone system, a connective switch, a called line, a test terminal of the called line, means for automatically operating the connective switch to effect selection of and seizure of the called line, means responsive to a specific electrical potential existing on said test terminal for barring the seizure of the selected called line, means for applying and removing said specific electrical potential from said test terminal, a call meter device for the called line, and means for operating said 120 125 130

- device to record a barred call to the called line only if said switch is operated into selective relation with the called line and said switch is prevented from seizing the called line due to the said specific potential existing on said test terminal thereof. 65
2. In an automatic telephone system, a connective switch, a called line, a test terminal of the called line, means for automatically operating the connective switch to effect selection of and seizure of the called line, means responsive to a specific electrical potential existing on said test terminal for barring the seizure of the selected called line, 10 means for applying and removing said specific electrical potential from said test terminal, a call meter device for the called line, and means for operating said device to record a barred call to the called line only if 15 said switch is operated into selective relation with the called line and said switch is prevented from seizing the called line due to the said specific potential existing on said test terminal thereof, and automatic means for 20 causing the operation of last said means only during certain predetermined periods of the day. 25
3. In an automatic telephone system, lines, a primary line switch for each said line, a group of secondary line switches accessible from said primary line switches, specifically distinctive tone sources for the primary line switches and for the group of secondary line switches, another switch accessible from said 30 secondary line switches, means responsive to initiating a call on a random one of said lines for causing the corresponding primary line switch to seize a said secondary line switch and for the seized secondary line switch to thereupon seize said other switch, means for barring a seized said switch from being further seized by another said switch while the first seizure endures, and means for applying the corresponding said tone source audible on 35 the concerned said line responsive to the initiation of a call on a random said line if the concerned primary line switch is barred from seizing all secondary line switches or if the secondary line switch seized by the primary 40 line switch is barred from seizing the said other switch. 45
4. In an automatic telephone system, lines, a primary line switch for each said line, a group of secondary line switches accessible from said primary line switches, sources of direct current specific to the primary line switches and to the group of secondary line switches, another switch accessible from said secondary line switches, means responsive to 55 initiating a call on a random one of said lines for causing the primary line switch to seize a said secondary line switch and for the seized secondary line switch to thereupon seize said other switch, means for barring 60
- seized said switch from being further seized by another said switch while the first seizure endures, and means for applying the corresponding said current source to a talking conductor of the concerned said line responsive to the initiation of a call on a random said line if the concerned primary line switch is barred from seizing all secondary line switches or if the secondary line switch seized by the latter said primary 65 line switch is barred from seizing the said other switch. 70
5. In an automatic telephone system, lines, a primary line switch for each said line, a group of secondary line switches accessible from said primary line switches, another switch accessible from said secondary line switches, means responsive to initiating a call on a random one of said lines for causing the corresponding primary line switch to seize a said secondary line switch and for the seized secondary line switch to thereupon seize said other switch, means for barring a seized said switch from being further seized by another said switch while the first seizure endures, and means for applying a tone audible on the said line responsive to the initiation of a call on a random said line if the concerned primary line switch is barred from seizing all secondary line switches or if the secondary line switch seized by the latter said primary 80 line switch is barred from seizing the said other switch. 85
6. In an automatic telephone system, lines, a primary line switch for each said line, a group of secondary line switches accessible from said primary line switches, another switch accessible from said secondary line switches, means responsive to initiating a call on a random one of said lines for causing the primary line switch to seize a said secondary line switch and the seized secondary line switch to thereupon seize said other switch, means for barring a seized said switch from being further seized by another said switch while the first seizure endures, and means for applying a source of direct current to a talking conductor of the concerned said line responsive to the initiation of a call on a random said line if the concerned primary line switch is barred from seizing all secondary line switches or if the secondary line switch seized by the latter said primary line switch is barred from seizing said other switch. 90
7. In an automatic telephone system, lines, a line switch, other switches, a source of direct current, another switch accessible from said line switch and said other switches, means responsive to initiating a call on one of said lines for causing said line switch to seize said another switch, means for barring said another switch from being further seized by one of said other switches responsive to said seizure only while said seizure endures, and means for applying said source of current. 120
- 125

rent to a talking conductor of any said other switches seeking to seize said another switch when it is barred against seizure.

8. In an automatic telephone system, a group of line switches, a group of lines accessible from said switches, a common conductor, a chain ground closed from said common conductor, an antecedent switch having common access to the switches of said group, a private busy conductor individual to each switch of said group for barring the corresponding switch against seizure by said antecedent switch, means for conductively connecting the private conductors of all switches of said group when idle to the common conductor, means for closing said chain ground to apply busy ground bar to all switches of said group to prevent the antecedent switch from seizing an idle switch of said group only if all the said group of lines accessible from said group of switches are busy, and means for disconnecting the private conductor of any switch responsive to the seizure of the corresponding switch by the antecedent switch, the said seizure being possible only when the switch seized is idle and there is an idle said line accessible from the switch seized.

9. In an automatic telephone system, a rotary line switch, a set of movable wipers of the switch, sets of fixed terminals of the switch swept by said wipers moving in a single direction, the wipers constantly engaging a random set of said fixed terminals, a line relay of the switch, a wiper switching relay of the switch, a group of lines corresponding to said fixed terminals, means for making random ones of said lines busy, means for preventing the wiper switching relay from operating when the wipers are resting upon the terminals of a busy said line, an antecedent switch having access to said switch, directly controlled means including said antecedent switch for causing the said relays to operate only when the wipers are resting upon the terminals of an idle said line, means for guarding the said line switch against seizure by the antecedent switch if one of said relays is actuated, and means for guarding said line switch against seizure by the antecedent switch if all said lines are busy although neither one of said relays is actuated, the last said means involving a circuit path including a normally closed contact on each said relay.

10. In an automatic telephone system, a calling line, a pre-payment device on the calling line, a called line, a train of automatic switches for linking a connection from the calling line to the called line, means responsive to initiating a call on the calling line only if the pre-payment device is operated by inserting a pre-payment therein for operating a first one of said automatic switches to link a preliminary call extension towards the called line, means thereafter directly con-

trolled over the calling line for operating other of said automatic switches to complete said extension to the called line, means responsive to abandoning the initiated call for causing the pre-payment device to refund the inserted pre-payment, and means operated responsive to said initiation only if the first said switch is barred from making said preliminary extension due to all call extension paths therefrom being barred as busy for causing the pre-payment device to refund the inserted pre-payment.

11. In an automatic telephone system, a calling line, a pre-payment device on the calling line, a called line, a train of automatic switches for linking a connection from the calling line to the called line, means responsive to initiating a call on the calling line only if the pre-payment device is operated by inserting a pre-payment therein for operating a plurality of said switches to link a preliminary call extension train towards the called line, means thereafter directly controlled over the calling line for operating other of said automatic switches to complete said extension to the called line, means responsive to abandoning the initiated call for causing the pre-payment device to refund the inserted pre-payment, and means operated responsive to said initiation only if one of said plurality of switches is barred from making said preliminary extension due to all call extension paths therefrom being barred as busy for causing the pre-payment device to refund the inserted pre-payment.

12. In a telephone system, a calling line, a called line, automatic switch mechanism for extending a connection from the calling line to the called line, a pre-payment device, means depending upon first operating said pre-payment device by a pre-payment for capacitating the operation of the said switch mechanism, a collecting receptacle and a refunding receptacle for the pre-payment device, means manually controlled over the called line only after the calling line has been extended to the called line for establishing a talking relation between the calling line and the called line, means for thereafter at will destroying the extended connection and for depositing said pre-payment in the refunding receptacle, and means controlled over the called line at will after establishing said talking relation and before destroying said extended connection for preventing said pre-payment from being deposited in the refunding receptacle.

13. In a telephone system, a calling line, a called line, automatic switch mechanism for extending a connection from the calling line to the called line, a pre-payment device, means depending upon first operating said pre-payment device by a pre-payment for capacitating the operation of the said switch mechanism, a collecting receptacle and a re-

funding receptacle for the pre-payment device, means manually controlled over the called line only after the calling line has been extended to the called line for establishing a 5 talking relation between the calling line and the called line, means for thereafter at will destroying the extended connection and for depositing said pre-payment in the refunding receptacle, means controlled over the 10 called line at will after establishing said talking relation and before destroying said extended connection for preventing said pre-payment from being deposited in the refunding receptacle, and means thereafter operated 15 responsive to destroying the extended connection for depositing said pre-payment in the collecting receptacle.

14. In a telephone system, a calling line, a called line, automatic switch mechanism for 20 extending a connection from the calling line to the called line, a pre-payment device, means depending upon first operating said pre-payment device by a pre-payment for capacitati- 25 ng the operation of the said switch mechanism, a collecting receptacle and a refunding receptacle for the pre-payment device, means manually controlled over the called line only after the calling line has been extended to the called line for establishing a talking relation 30 between the calling line and the called line, means for thereafter at will destroying the extended connection and for depositing said pre-payment in the refunding receptacle, means controlled over the called line at will 35 after establishing said talking relation and before destroying said extended connection for preventing said pre-payment from being deposited in the refunding receptacle, and means thereafter operated at the termina- 40 tion of a predetermined period of time for conversation following the said control of last said means for depositing said pre-payment in the collecting receptacle.

15. In a telephone system, a calling line, a called line leading from a central exchange 45 to a subscriber's station, automatic switch mechanism for extending a call connection from the calling line to the called line, a toll assessing device for the called line at the central exchange, and means controlled over the 50 called line for operating the toll assessing device after said extension to the called line has been made to record a toll assessment for the call connection from the calling line to the 55 called line against the called line without recording a toll assessment against the calling line.

16. In a telephone system, a calling line, a called line, automatic switch mechanism for 60 extending a call connection from the calling line to the called line, a toll assessing device for the calling line, a toll assessing device for the called line, means responsive to a manual operation on the called line for operating the toll assessing device only of the

called line, and other means operated responsive to a manual operation on the called line applied at will while said connection exists for operating the toll assessing device for the calling line and for disabling the operation 70 of the toll assessing device on the called line.

17. In a telephone system, a calling line, a called line, automatic switch mechanism for extending a call connection from the calling line to the called line, a toll assessing device 75 for the calling line, a toll assessing device for the called line, and means controlled over the called line by a manual operation for defining what portions of the total toll charge for the call shall be respectively as- 80 sessed against the calling line and the called line on the corresponding said devices.

18. In a telephone system, a calling line, a called line, automatic switch mechanism for 85 extending a call connection from the calling line to the called line, a toll assessing device for the calling line, a toll assessing device for the called line, means on the called line manually operated for completing a talking connection between the connected calling and 90 called lines and means depending upon the time of day the last said means is operated for determining whether the toll charge for the talking connection will be recorded against the calling line or the called line by its corre- 95 sponding toll assessing device.

19. In telephone system, a calling line, a called line, automatic switch mechanism for extending a connection from the calling line to the called line, a pre-payment 100 device, means depending upon first operating said pre-payment device by a pre-payment for capacitati- 105 ng the operation of the said switch mechanism, a collecting receptacle and a refunding receptacle for the pre-payment device, means for causing the pre-payment device to deposit the pre-pay- 110 ment in the collecting receptacle in a substan- tially pre-determined time variable in length depending upon the time of day the said time 115 durates through, a first and a second specific- 120 ally distinctive tone source, means for applying one said tone source audible on the calling line at a substantially predetermined time before the termination of said period, and means for applying the other of said tone sources audible on the calling line at a sub- 125 stantially predetermined time before the termination of said period, the elapsed time between the said applications of the tone sources being substantially constant for a plurality of calls regardless of the fact that the length of the said period may vary among said plurality of calls, so that a listener on the calling line will have substantially definite notice of the times remaining of a said period regardless of the length of the period.

20. In an automatic telephone system, a called line, an automatic connective switch for effecting connection to said called line, 130

- 1 a private terminal of the called line, means for applying a specific electrical potential to the private terminal indicative of the busy condition of the called line, 5 means responsive to effecting connection to the called line when it is busy for preventing the switch from effecting seizure of the connected called line so that a talking relation between the switch and the busy called line 10 is barred, a tone source, and means operated for applying the tone source to a talking conductor of the called line responsive to the switch effecting connection to the called line whether busy or idle.

15 21. In a telephone system, a called line, switch mechanism for extending connection to said line, a toll assessing device for the called line, means controlled over the called line for operating the toll assessing device, 20 and means dependent upon the time of day the connection is made to the called line for determining the extent of said assessment.

25 22. In a telephone system, a called line, switch mechanism for extending connection to said line, a toll assessing device for the called line, means controlled over the called line for operating the toll assessing device, and means dependent upon the duration of 30 the connection for determining the extent of said assessment.

35 23. In a telephone system, a called line, switch mechanism for extending connection to said line, a toll assessing device for the called line, means controlled over the called line for operating the toll assessing device, and means dependent upon the time of day the connection is made to the called line for determining whether or not the assessment 40 will be made.

45 24. In a telephone system, a called line, switch mechanism for extending connection to said line, a toll assessing device for the called line, means controlled for initiating the operation of the toll assessing device for causing a plurality of assessments to be successively made against the called line, and means controlled over a series path of a talking conductor of the called line at will for preventing further said assessments being thereafter made while maintaining the connection.

50 25. In a telephone system, a calling line, a called line, automatic switch mechanism for extending connection from the calling line to the called line, a toll assessing device for the calling line, a timing device for measuring elapsed time, means controlled over the called line for initiating the operation of said timing device, means responsive to the operation of said timing device for assessing a toll charge on said toll assessing device, means for periodically reoperating said timing device for assessing accruing toll charge on said toll assessing device, and means the operation of which is dependent upon whether the assessment is the initial assessment for a call or

55 a succeeding assessment for said call for determining the length of time the toll assessment covers.

60 26. In a telephone system, a calling line, a called line, automatic switch mechanism for extending connection from the calling line to the called line, a toll assessing device for the calling line, a timing device individual to the connection for measuring elapsed time, means controlled over the called line for initiating from rest the operation of the timing device, means responsive to the operation of said timing device for assessing a toll charge on said toll assessing device, means for periodically reoperating said timing device for assessing accruing toll charge on said toll assessing device, and means governed by the time of day the call transpires for determining the length of time the respective said assessments cover.

65 27. In a telephone system, a calling line, a called line, automatic switch mechanism for extending connection from the calling line to the called line, a toll assessing device for the called line, a timing device for measuring elapsed time, means controlled over the called line for initiating the operation of said timing device, means responsive to the operation of said timing device for assessing a toll charge on said toll assessing device, means for periodically reoperating said timing device for assessing accruing toll charge on said toll assessing device, and means the operation of which is dependent upon whether the assessment is the initial assessment for a call or a succeeding assessment for said call for determining the length of time the toll assessment covers.

70 28. In a telephone system, a calling line, a called line, automatic switch mechanism for extending connection from the calling line to the called line, a toll assessing device for the called line, a timing device for measuring elapsed time, means controlled over the called line for initiating the operation of said timing device, means responsive to the operation of said timing device for assessing a toll charge on said toll assessing device, means for periodically reoperating said timing device for assessing accruing toll charge on said toll assessing device, and means governed by the time of day the call transpires for determining the length of time the respective said assessments cover.

75 29. In a telephone system, a calling line, a called line, automatic switch mechanism for extending talking connection from the calling line to the called line, a toll assessing device for defining a predetermined toll charge against the calling line for the connection to the called line and for a predetermined duration period of said connection, a progressively movable wiper switch for measuring elapsed time of said connection for said charge, means for thereafter defining an ad-

ditional period of continued connection by a further movement of said movable wiper switch, and automatic means for varying the length of individual successive said periods 5 for a single said connection depending upon the duration of said connection.

30. In a telephone system, a calling line, a primary line switch for the calling line, primary lines accessible from the primary line switch, a secondary line switch for the respective said primary lines, secondary lines accessible from said secondary line switches, means operated responsive to initiating a call on the calling line for causing the primary line switch to hunt for and connect to a said primary line and for thereupon causing the corresponding secondary line switch to hunt for and connect to a said secondary line, means for making said primary lines and said secondary lines busy, means for barring busy said lines against connection to by the cooperative said switches, means responsive to an all busy condition of said secondary lines for preventing the primary line switch from connecting 25 to the primary line, and means whereby responsive to an all busy condition of said secondary lines occurring after a primary line has been connected to by a primary line switch and before its corresponding secondary line switch has connected to a secondary line, a busy indication will be applied discernible on the calling line to indicate that the calling line has been barred from extension to a said secondary line.

35. 31. In a telephone system, a calling line, a primary line switch for the calling line, primary lines accessible from the primary line switch, a secondary line switch for the respective said primary lines, secondary lines accessible from said secondary line switches, means operated responsive to initiating a call on the calling line for causing the primary line switch to hunt for and connect to a said primary line and for thereupon causing the corresponding secondary line switch to hunt for and connect to a said secondary line, means for making said primary lines and said secondary lines busy, means for barring busy said lines against connection to by the cooperative said switches, means responsive to an all busy condition of said secondary lines for preventing the primary line switch from connecting to a primary line, means whereby responsive to an all busy condition of said secondary lines occurring after a primary line has been connected to by a primary line switch and before its corresponding secondary line switch has connected to a secondary line, a busy indication will be applied discernible on the calling line 40 to indicate that the calling line has been barred from extension to a said secondary line, and means responsive to the all busy condition of the secondary lines terminating for stopping the application of the busy indication and for causing the secondary line

switch to operate and complete the connection from the calling line to an idle said secondary line.

32. In a telephone system, a calling line, a primary line switch for the calling line, primary lines accessible from the primary line switch, a secondary line switch for the respective said primary lines, secondary lines accessible from said secondary line switches, means operated responsive to initiating a call 70 on the calling line for causing the primary line switch to hunt for and connect to a said primary line and for thereupon causing the corresponding secondary line switch to hunt for and connect to a said secondary line, means 75 for making said primary lines and said secondary lines busy, means for barring busy said lines against connection to by the cooperative said switches, and means including a circuit path from ground individual to each 80 said secondary line switch and a contact of a relay of latter said switch responsive to all said secondary lines becoming busy for preventing the primary line switch from connecting to a primary line.

33. In a telephone system, a calling line, a primary line switch for the calling line, primary lines accessible from the primary line switch, a secondary line switch for the respective said primary lines, secondary lines accessible from said secondary line switches, means operated responsive to initiating a call 90 on the calling line for causing the primary line switch to hunt for and connect to a said primary line and for thereupon causing the corresponding secondary line switch to hunt for and connect to a said secondary line, means 95 for making said primary lines and said secondary lines busy, means for barring busy said lines against connection to by the cooperative said switches, and means including a circuit path from ground individual to each 100 said secondary line switch and a contact of a relay of latter said switch responsive to all said secondary lines becoming busy for preventing the primary line switch from connecting to a primary line, and means for disabling said circuit path at said contact when the secondary line switch is in its connected condition 110 with respect to a secondary line.

34. In a telephone system, a calling line, a primary line switch for the calling line, primary lines accessible from the primary line switch, a secondary line switch for the respective said primary lines, secondary lines accessible from said secondary line switches, means operated responsive to initiating a call 115 on the calling line for causing the primary line switch to hunt for and connect to a said primary line and for thereupon causing the corresponding secondary line switch to hunt for and connect to a said secondary line, means 120 for making said primary lines and said secondary lines busy, means for barring busy said lines against connection to by the cooperative said switches, and means including a circuit path from ground individual to each 125 said secondary line switch and a contact of a relay of latter said switch responsive to all said secondary lines becoming busy for preventing the primary line switch from connecting to a primary line, and means for disabling said circuit path at said contact when the secondary line switch is in its connected condition 130 with respect to a secondary line.

operative said switches, means responsive to an all busy condition of said secondary lines for preventing the primary line switch from connecting to a primary line, and means for applying a busy indication discernible on the calling line responsive to said busy condition of all said secondary lines.

35. In a telephone system, a calling line, a called line, common automatic switch mechanism for completing a call connection from the calling line to the called line, a toll assessing device for the called line for recording toll charges, first automatic means operated by control over the called line responsive to answering the call for causing the toll charge for a call from the calling line to the called line to be thereafter assessed on said device, second automatic means for causing said automatic switch mechanism to become freed from its connective relation with the called line, and automatic means for arresting the effective operation of last said means only until the toll charge for said call has become registered on said device, but provided said first automatic means has been operated, to insure that regardless of the fact that the charge has not yet been assessed responsive to the operation of said first automatic means when said second automatic means has been operated said switch mechanism will remain connected with the called line until the assessment has been made.

36. In a telephone system, a calling line, a called subscriber's line, switch mechanism for extending a call connection from the calling line to the called line, a toll assessing device for the called line, automatic means operated responsive to control over the connection to called line for operating the toll assessing device to assess a toll against the called line, and automatic means operated under control of the subscriber of the called line, over the called line, for preventing the assessment of the toll against the called line although said connection to the called line is continued.

37. In a telephone system, a calling line, a called subscriber's line, switch mechanism for extending a call connection from the calling line to the called line, a toll assessing device for the called line, a toll assessing device for the calling line, and automatic means operated over a talking conductor of the called line for determining which said toll assessing device will record the toll for the call connection.

38. In a telephone system, a calling line, a called subscriber's line, switch mechanism for extending a call connection from the calling line to the called line, a toll assessing device for the called line, a toll assessing device for the calling line, and automatic means the operation of which is governed by the time of day for determining which said toll as-

sessing device will record the toll for the connection.

39. In a telephone system, a calling line, a called subscriber's line, switch mechanism for extending a call connection from the calling line to the called line, a toll assessing device for the called line, a toll assessing device for the calling line, first automatic means operated over the called line for causing first said toll assessing device to record the toll for the call connection, and a second automatic means controlled over the called line for causing second said toll assessing device to record the toll for the call connection in lieu of first said toll assessing device.

40. In an automatic telephone system, a calling line, a toll assessing device for recording toll charge against the calling line, a called line, an automatic numerical switch used in linking a connection from the calling line to the called line directly operated responsive to at least one digit of the numerical designation of the called line, a timing switch for first said switch for operating the toll assessing device to cover a period of time of connection, automatic means operated over the called line for initiating the operation of the timing switch, and means for preventing the disconnection from the connection of first said switch after the operation of the timing switch has been initiated until a toll charge for the ensuing period has been registered on the toll assessing device and the timing switch has restored to the condition as at the time its said operation was initiated.

41. In an automatic telephone system, a calling line, a toll assessing device for recording toll charge against the calling line, a called line, an automatic numerical switch used in linking a connection from the calling line to the called line directly operated responsive to at least one digit of the numerical designation of the called line, a second switch of the connection located between said numerical switch and the called line, a timing switch for first said switch for operating the toll assessing device to cover a period of time of connection, automatic means operated over the called line for initiating the operation of the timing switch, means operated over the calling line for disconnecting said second switch from the connection to the called line, and means for at the same time preventing the disconnection from the connection of first said switch after the operation of the timing switch has been initiated until a toll charge for the ensuing period has been registered on the toll assessing device and the timing switch has restored to the condition as at the time its said operation was initiated.

42. In an automatic telephone system, a calling line, a toll assessing device for recording toll charge against the calling line, a called

line, an automatic numerical switch used in linking a connection from the calling line to the called line directly operated responsive to at least one digit of the numerical designation of the called line, a non-numerical switch of the connection antecedent to said numerical switch, a timing switch for first said switch for operating the toll assessing device to cover a period of connection, automatic means operated over the called line for initiating the operation of the timing switch, means for maintaining the calling line connected through the non-numerical switch with the numerical switch after the operation of the timing switch has been initiated until a toll charge for the ensuing period has been registered on the toll assessing device, regardless of the fact control has been exercised over the calling line for breaking down the connection from the calling line to the called line, and automatic means for causing the connection to be destroyed at each said switch responsive to the toll being assessed and the timing switch having restored to its condition as when its operation was initiated, following last said control.

43. In a telephone system, a called line, switch mechanism for extending connection to said line, a toll assessing device for the called line, means controlled for initiating the operation of the toll assessing device for causing a plurality of assessments to be successively made against the called line, and automatic means operated in predetermined manner for signaling the subscriber on the called line a substantially predetermined time before a new assessment is to be made, in order that the call may be terminated to avoid said new assessment being made.

44. In a telephone system, a calling line, a called line, a common automatic switch used in linking a connection from the calling line to the called line, a call toll assessing device for the calling line, a timing switch for said automatic switch for operating said toll assessing device, means operated over the called line for initiating the operation of the timing switch, means operated over the calling line for directly causing the automatic switch to become free from the connection, and automatic means for arresting the effective operation of last said means only until the toll charge for said call has become assessed by said device but provided that the operation of the timing switch has been initiated, to insure that regardless of the fact that the charge has not already been assessed when the automatic means for directly freeing the automatic switch from the connection has been operated the automatic switch will remain connected with the calling line until the assessment has been made, under the condition only that the call has been answered.

45. In a telephone system, a calling line, a called line, an automatic switch used in link-

ing a connection from the calling line to the called line, a call toll assessing device for the calling line, a common timing switch for said connection for operating said toll assessing device, means operated over the called line for initiating the operation of the timing switch, means operated over the calling line for directly causing the said automatic switch and said timing switch to become free from the connection, and automatic means for arresting the effective operation of last said means only with respect to freeing said timing switch from the connection and only until the toll charge for said call has become assessed by said device but provided the operation of the timing switch has been initiated, to insure that regardless of the fact that the charge has not already been assessed when the automatic means for directly freeing the timing switch from the connection has been operated the timing switch will remain connected with the calling line until the assessment has been made, under the condition only that the call has been answered.

46. In an automatic telephone system, a calling line, a called line, a non-numerical switch and a successively positioned numerical switch for linking a connection from the calling line to the called line, a call assessing device for the calling line, a timing switch for said numerical switch and operatively associated with said numerical switch during the time of said connection, a release trunk leading back from the numerical switch to the non-numerical switch for sustaining the numerical switch in connection with the calling line by ground applied back to the non-numerical switch, means operated over the called line consequent to answering the call for initiating the operation of the timing switch, means directly operated over the calling line for causing the disconnection of the calling line from the numerical switch and associated timing switch, and means for maintaining the said ground on the release trunk to sustain the connection only until the timing switch has caused the assessment for the call on the call assessing device for the ensuing time period, and has returned to its position occupied at the time its operation was initiated.

47. In an automatic telephone system, a calling line, a called line, a non-numerical switch and a successively positioned numerical switch in a connection linking the calling line and the called line, a release trunk for maintaining the calling line connected through the non-numerical switch with the numerical switch by a potential applied back from the numerical switch to the non-numerical switch, an auxiliary switch having a progressive movement companion to the numerical switch, a normal resting position and off-normal position for the auxiliary switch, means controlled over the called line for

initiating the operation of the auxiliary switch from normal and back to normal again, means operated over the calling line for removing said potential from the release trunk 5 to break down the connection from the calling line to the called line, and means depending upon the off-normal position of the auxiliary switch for maintaining said potential on the release trunk only until the auxiliary 10 switch returns to normal position, so that regardless of the control over the calling line to remove said potential, the release trunk will continue to present said potential to sustain the connection only while said auxiliary switch is in an off-normal position.

48. In a telephone system, a calling line, a called line, a prepayment toll assessing device, automatic switch means for linking connection from the calling line to the called line, 15 a progressively movable timing switch of the connection for operating the toll assessing

device to record a toll charge for a predetermined period of connection, signaling means operated by the timing switch for notifying a party of the connection of the amount of 20 remaining time of said predetermined period, automatic means operated by the timing switch for disabling talking service over the connection responsive to the predetermined period expiring, means for holding 25 the switch means of the connection in its operated position for only a predetermined time after said disablement in order to allow time for again prepaying for an additional period of connection, and means responsive 30 to the latter said prepayment, only if made within last said predetermined time, for again establishing the talking relation between the calling line and the called line.

In witness whereof, I hereunto subscribe 40 my name this thirteenth day of July, 1927.

HERBERT M. FRIENDLY.
